(57) **CLAIM**

The ornamental design for a bench, as shown and described.

DESCRIPTION

FIG. 1 is a front elevational view of the bench showing my new design;

FIG. 2 is a rear elevational view thereof;

FIG. 3 is a right side elevational view thereof;

FIG. 4 is a top plan view thereof;

FIG. 5 is a bottom view thereof;

FIG. 6 is a cross-sectional view thereof taken along the line 6-6 in FIG. 1;

FIG. 7 is a front perspective view thereof;

FIG. 8 is a rear perspective view thereof;

FIG. 9 is a perspective view thereof in an environment of use;

FIG. 10 is a perspective view thereof in an environment of use; and,

FIG. 11 is a perspective view thereof in an environment of use.

The broken lines in the figures are to show environment and form no part of the claimed design.

1 Claim, 11 Drawing Sheets
